INSULATOR

Robert D. Jones, Kramer, via Hinkley, Calif.,
assignor to Georgia H. Duncan, Kramer, via
Hinkley, Calif.

Application October 8, 1934, Serial No. 747,434

5 Claims. (Cl. 173—313)

This invention relates to insulators for electric conductors and has as its object the provision of an insulator having as an integral part thereof a metal clamp for the attachment of an electric conductor or wire to the insulator.

5 My insulator has the following advantages over types now in use:

It eliminates induction leakage occasioned by coils formed by tie wires.

10 It increases arcing radius between conductor and ground contact.

It eliminates the building up of static within confines of groove in which tie wires are laid.

15 The major cause for surface leakage in insulators now in use is from small particles of metal that are removed by erosion from wires occasioned by expansion and contraction and by swinging in wind. These minute particles adhere to the surface of the insulator forming a path of conductive matter which superinduces 20 surface leakage. My insulator eliminates this as the wire cannot creep to cause friction between conductor and insulator.

25 Wires will constantly maintain their initial length between supports.

It facilitates the initial operation of installation and lowers the cost of maintenance.

30 In its construction, the member including the lower jaw is built with and into the insulator body and nothing protrudes to hinder packing and shipping of the insulator.

35 In the process of clamping the conductor to my insulator no force necessary to hold the wire in clamped relation is directed against the dielectric from which the insulator body is made.

It is adaptable efficiently and economically to 40 lines of voice frequency as well as to lines of high voltage.

As no static can build up within the confines of 45 the unit, there can be no corona discharge and no interference with radio waves.

The invention, together with its objects and advantages, will be best understood from a study of the following description, taken in connection 50 with the accompanying drawing, wherein:

Figure 1 is an elevational view of a portion of an insulator having that part thereof forming the clamp associated therewith, the member comprising the clamp being shown in section, and 55 parts of the insulator body being broken away. The lower part or skirt of the insulator is not shown, as I do not limit myself to any specific shape of insulator skirt. Any form of insulator skirt may be employed and still be within the 60 scope of my invention.

Figure 2 is an exploded view of that part of the insulator forming the clamp.

Figure 3 is an elevational view of that part of the insulator forming the clamp with the parts thereof assembled.

5 Figure 4 is a perspective view of a jaw forming part of the clamp.

Referring to the drawing by reference numerals, it will be seen that 5 indicates generally a vitreous or ceramic insulator of known construction. In accordance with the present invention, the dielectric body of the insulator has fixedly embedded in the crown thereof and in immediate contact therewith an internally threaded socket 6 which at its lower end is provided with a point 1 and above the point 1 with lateral projections or fins 8 serving to securely anchor the socket within the body of the insulator. The spaced fins 8 allow the viscous material from which the insulator is cast to pass unobstructed into the mold without forming air bubbles or pockets and congeal about the socket member to form a strong anchorage in the process of manufacture. At the upper end thereof, the socket is formed into an en bloc therewith a concavo-convex head 20 or jaw 9 which projects from all sides of the socket and whose underface is concave so as to present an edge 10 that is embedded within and in immediate contact with the dielectric material of the insulator body in a manner clearly shown 25 in Figure 1. The jaw 9 laterally of the socket 6 is formed with a toothed gripping concave channel 11 and a groove 17 extending lengthwise of the jaw 9 at the side of the concave face 11 opposite the socket 6. Socket 6 is eccentric with 30 respect to the head or jaw 9. The dielectric body 5 is molded about the socket 6 and head 9 while the body material is in the molten or plastic condition.

35 A removable jaw 13 is provided with a gripping concave channel 14 cooperable with the concave channel 11 of the jaw 9 for clamping therebetween the electric conductor or wire 15 as shown in Figure 1. At one end thereof the jaw 13 is provided with a tongue 16 that fits in the groove 40 17 in a manner to retain the jaw 13 against rotative movement, and to adapt the clamp for use on conductors of different sizes.

The jaw 13 also has an apertured end thereof 45 alining with the bore of the socket 6 so as to accommodate a clamping screw 18 that is adapted to be screwed into the socket 6 as clearly shown in Figure 1. A split spring washer 19 is disposed about the screw 18 between the head of the screw 50 and the top face of the jaw 13 and this washer 55

serves to lock the screw when the same has been threaded home inwardly of the socket 6.

A feature of the present invention is the mushroom shaped jaw-equipped member comprising head 9 and socket 6, being constructed of one and the same piece of metal, and so shaped that when the strain of the load is placed upon it, it will act in the nature of a complex inverse lever, the power being at 15, the fulcrum at 20 and the complex weights at 7 and 10, offering the resistance of such regardless of the direction in which the pull or power may be applied. Thus, with this construction, before the end 1 of the embedded member can yield in any direction to the power or pull of the line wire from any direction, half of the concave surface of the mushroom head 9 must also move downward and towards the center of the insulator body 5 in which it is embedded. The insulator, if sufficient strain were put upon it in a manner in which its construction is purposed to resist, would break at the pin attaching it to the pole before it would collapse where the member is embedded.

What is claimed is:

25 1. An insulator comprising a dielectric body adapted for attachment to a support, a conductor wire clamp including coacting removable and fixed jaws the latter being anchored to the dielectric body, said fixed jaw comprising a head formed with a recess on the face confronting the dielectric body, a socket member depending from the head in eccentric relation with respect to the recess, and said recess and said socket member being in contact with the dielectric body.

30 2. An insulator comprising a congealed thermoplastic dielectric body adapted for attachment to a support, a conductor wire clamp including coacting removable and fixed jaws the latter being anchored to the dielectric body, said fixed jaw comprising a head and a socket member depending therefrom, said head formed with a recess confronting the dielectric body, said socket member disposed in eccentric relation with respect to the recess, and said dielectric body congealed 45 about the socket member and against the walls of the recess in the head.

35 3. An insulator comprising a congealed thermoplastic dielectric body adapted for attachment to a support, a conductor wire clamp including coacting removable and fixed jaws, said fixed jaw comprising a concavo-convex head and an integral socket member depending therefrom, the dielectric body being congealed against the concave face of the head, said socket member disposed in eccentric relation with respect to the

recess, said socket member formed with a point on the free end and radially extending circumferentially spaced fins adjacent the free end; and said dielectric body being congealed about the socket member, fins and point.

4. An insulator comprising a congealed thermoplastic dielectric body adapted for attachment to a support, a conductor wire clamp including a fixed jaw and a removable jaw, said fixed jaw formed with a head having upper and lower faces and a socket member depending in eccentric relation with respect to the head, said head formed with a recess in the lower face, said dielectric body congealed about the socket member and against the walls of the recess in the lower face, 15 said head and socket member formed with a threaded socket, on the upper face said head being formed with a serrated conductor wire channel laterally of the threaded socket and a groove extending outwardly from said channel, a bolt 20 for detachable mounting in said threaded socket, said removable jaw mounted on the bolt and formed with a serrated channel and a tongue extending outwardly therefrom registering with the channel and groove on the head of the fixed jaw 25 whereby a conductor wire is clamped in the channels and the removable jaw is prevented from turning on the bolt.

5. An insulator comprising a congealed thermoplastic dielectric body adapted for attachment to a support, a conductor wire clamp including coacting removable and fixed jaws the latter being anchored to the dielectric body, said fixed jaw comprising a concavo-convex head and an integral socket member depending in eccentric relation with respect to the concaved face of the head, said socket member formed with a point on the free end and radially extending circumferentially spaced fins adjacent the free end, said dielectric body congealed against the concaved 40 face of the head and about the fins and the point, said head and socket member formed with a threaded socket, the convex face of said head formed with a serrated conductor wire channel laterally of the threaded socket and a groove 45 extending outwardly from said channel, a bolt for detachable mounting in said threaded socket, and said removable jaw mounted on the bolt and formed with a serrated channel and a tongue extending outwardly therefrom registering with the channel and groove on the head of the fixed jaw 50 whereby a conductor wire is clamped in the channels and the removable jaw is prevented from turning on the bolt.
